UNITED STATES PATENT OFFICE.

EDWIN HORICE HANEY, OF FRENCH CAMP, CALIFORNIA, ASSIGNOR TO HANEY FIRE APPARATUS CO., OF STOCKTON, CALIFORNIA, A CORPORATION.

FIRE-ESCAPE.

1,027,724.

Specification of Letters Patent.

Patented May 28, 1912.

Application filed June 7, 1910. Serial No. 565,632.

To all whom it may concern:

Be it known that I, EDWIN H. HANEY, a citizen of French Camp, county of San Joaquin, State of California, have invented 5 certain new and useful Improvements in Fire-Escapes; and I do declare the following to be a full, clear, and exact description of the same, such as will enable others skilled in the art to which it appertains to 10 make and use the same, reference being had to the accompanying drawings; and to the characters of reference marked thereon, which form a part of this application.

This invention relates to improvements in 15 fire escapes, the object of the invention being to produce a means whereby fires on high buildings may be successfully fought and extinguished from the outside of the building, as well as permitting inmates to 20 be saved by reason of the fact that my device is designed to permit the firemen to go above a burning portion of a building and save lives and property before the fire reaches the same, whereas in the present day 25 method often the fire shuts off the work of rescue.

A further object of the invention is to 30 produce a comparatively simple and inexpensive device and yet one which will be exceedingly effective for the purposes for which it is designed.

These objects I accomplish by means of 35 such structure and relative arrangement of parts as will fully appear by a perusal of the following specification and claim.

In the drawings similar characters of reference indicate corresponding parts in the several views.

Figure 1 is a side view of a building 40 showing my improved structure thereon. Fig. 2 is a perspective view of a fire fighting cage. Fig. 3 is a sectional view taken on a line $x-x$ of Fig. 2. Fig. 4 is a sectional view taken on a line $y-y$ of Fig. 2. Fig. 5 is a fragmentary side view of a cable and pulley mechanism. Fig. 6 is an end view of a connecting bar and pulley mechanism. Fig. 7 is a side view of the same. Fig. 8 is 45 a side view of an automatic floor indicator.

Referring now more particularly to the characters of reference on the drawings, 1 designates a cage made of suitable metal and lined with asbestos and having suitable braces and to be water proof and fireproof

55 by the usual known expedients for that purpose. Such cage 1 has supporting rollers 1^a and a sliding door 2 moving on rollers 3 and having an inner operating handle 4.

In practice a building 5 would be provided with a projecting beam 6 at its top, 60 such beam having a cable 7 secured at one point 8 such cable then extending through a pulley 9 on a supporting bar 10 then through a pulley 11 on the beam 6 then through another pulley 12 on the bar 10 and 65 back through a pulley 13 on the beam 6 and thence normally connecting by a ring 14 with a hook 15 at the base of the building 5.

In case of a fire the firemen arrive carrying 70 with them the cage 1 which is at once connected with the bar 10 by means of eyes or rings 16 which receive snap hooks 17 on the bar 10. The cable 7 is then suitably connected with a drum 18 within the car 1 such 75 drum being operated by an engine 19 driving a shaft 20 driving in turn a shaft 21 by a belt 22 working over pulley 23 and 24 respectively. On the shaft 21 is a friction clutch 25 operated by a lever 26 to drive 80 a gear 27 intermeshing with a gear 28 to drive a shaft 29. This shaft 29 drives a gear 30 which in turn drives a gear 31 on the shaft 32 of the drum 18 thus driving said drum. 85

The operation of the drum winds up the cable 7 rapidly thus raising the cage 1 to any height on the building desired. When any desired height is reached and it is desired to enter the building through a window or the like, then a bridge or ladder 33 having rings 34 swiveled onto and 90 slideable on a longitudinal rod 35 on the underside of the cage is dropped through the window permitting the firemen to enter the 95 building to carry away persons or property. When not in operation this bridge or ladder 33 is held in normal vertical position by means of cables 36 extending through longitudinal rollers 37 on the top of the 100 cage 1 and thence over a roller 38 under a hood 39 and thence into the cage 1 and around drums 40 on a shaft 41 held normally stationary by a chain 42 connecting with a shaft 43 having a ratchet wheel 44 105 held by a ratchet dog 45. When the bridge or ladder 33 is to be dropped as above described, the dog 45 is released from the

wheel 44 allowing the weight of such bridge or ladder 33 to fall and smash into the window as aforesaid. Then when it is desired to raise it again the dog 45 is dropped into position in the wheel 44 and a handle crank 46 is operated to raise the same by the cables as aforesaid.

In order that ladder 33, cables 36 and drums 40 may always be in alinement with each other to insure successful operation the drums 40 are slidably keyed on the shaft 41 and are provided with a connecting sleeve 40^a which keeps them spaced at the proper distance apart. Thus when the ladder 15 moves along these drums 40 move along to keep in alinement therewith.

The operation of the shaft 20 drives a dynamo 47 to furnish power to operate a fan 48 to drive the smoke and heat from 20 the cage 1 and also to operate one or more lights 49.

50 are hooks for holding the fire hose 51. With every revolution of the shaft 32 it causes a dog 53 on a drum 54 to make a dog 25 55 operate a ratchet wheel 56 whereby every third revolution, (which has been previously determined will raise the cage one story on a building) will cause an arm 57 on said wheel 56 to operate an indicator 30 58 to show at which story the cage is as shown in Fig. 8. Similarly with every revolution of the shaft 32 a dog 59 on said shaft strikes a lever 60 which operates arms 61 to drive links 62 to operate other levers 35 63 having balls 64 which strike gongs 65 thus giving the alarm, to persons in the building, of the fire and the approaching of the cage. The normal operative position of said parts is maintained by a 40 spring 66.

67 is the fuel tank for the engine 19 and 68 the water tank connected with said engine by supply pipes 69 and 70 respectively.

The drum 18 has hand brakes 18^a op-

erated by screw rods 18^b which permit a 45 perfect control of the cage 1.

All the necessary fire fighting apparatus may be placed in the cage 1.

From the foregoing description it will be readily seen that I have produced such a 50 fire fighting apparatus as substantially fulfills the object of the invention as set forth herein.

While this specification sets forth in detail the present and preferred construction 55 of the device, still in practice such deviations from such detail may be resorted to as do not form a departure from the spirit of the invention.

Having thus described my invention what 60 I claim as new and useful and desire to secure by Letters Patent is:

A device of the character described comprising the combination of a cage, means to raise or lower said cage, such cage being 65 provided with a door, a rod extending along the bottom edge of said cage on the side in which said door is located, a ladder movable longitudinally on said rod, a driven shaft within said cage, drums slidably keyed 70 to said shaft, a sleeve connecting said drums, cables secured to said drums and to the outer end of said ladder, a sprocket wheel on said shaft, another sprocket wheel mounted independently of said shaft within 75 said cage, chains connecting said sprocket wheels, an operating handle on said last named sprocket wheel, a ratchet wheel in said last named sprocket wheel, a dog pivoted independently of said last named 80 sprocket wheel and normally engaging said ratchet wheel as described.

In testimony whereof I affix my signature in presence of two witnesses.

EDWIN HORICE HANEY.
